UNITED STATES PATENT OFFICE.

WILLIAM F. HUTCHINSON, OF VALATIE, NEW YORK, ASSIGNOR TO AMERICAN SPLINT CORPORATION, A CORPORATION OF NEW JERSEY.

MACHINE FOR CUTTING SHEET-STOCK.

1,179,835.

Specification of Letters Patent. Patented Apr. 18, 1916.

Application filed July 7, 1915. Serial No. 38,440.

To all whom it may concern:

Be it known that I, WILLIAM F. HUTCHINSON, a citizen of the United States, and a resident of Valatie, Columbia county, New York, have invented a new and useful Improvement in Machines for Cutting Sheet-Stock, of which the following is a full, clear, and exact description.

My invention relates to improvements in machines for cutting sheets of stock into more or less finely divided articles such as toothpicks, match splints, or other analogous things.

In carrying out my invention I employ a rotary cutter head in which the radial knives shear across or turn in close proximity to a single cut-off knife, and the stock is fed across the cut-off knife to the cutter head and is carried by the cutter head across the edge of the cut-off knife so as to sever the stock. Heretofore in machines of this character the cut-off knife has been stationary, and it has been found practically impossible to cut fibrous material with an arrangement of this kind; but in my invention I keep the cut-off knife moving and preferably sliding longitudinally at all times, so that as the stock is carried across it by the cutter head, the cut-off knife having a sliding movement will smoothly sever the stock, and it will have a drawing cut.

Another object of my invention is to provide an improved feed and scoring arrangement by which a relatively wide sheet of stock can be fed and severed into a series of parallel strips, which strips will be carried over the cut-off knife to the cutter head and rapidly cut into articles of the desired dimension.

Another object of my invention is to provide means for changing the feed conveniently, so that articles of different sizes can be cut on the same machine. In my invention I employ a cutter head having numerous radial blades or knives which are spaced apart a distance greater than the thickness of the stock, and with considerable depth, and these blades rotating in close proximity to the cut-off knife, carry the stock across the knife by which it is severed. It will be seen then that the width of these formed articles will depend on the speed of the feed, that is the depth to which the stock is permitted to enter between the blades of the rotary cutter head.

A principal object of my invention is to produce a simple, durable and reliable machine of the character above specified, which will work with remarkable rapidity.

My invention is also intended to produce a machine which can be very easily adapted to the purpose of cutting box blanks for small boxes, such as wooden match boxes, confectionery boxes, and the like.

Reference is to be had to the accompanying drawings forming a part of this specification, in which similar reference characters indicate corresponding parts in all the views.

Figure 1 is a plan view of the machine embodying my invention. Fig. 2 is an end view of the same. Fig. 3 is a vertical section on the line 3—3 of Fig. 1. Fig. 4 is a broken detail end view of a part of the cutter head. Fig. 5 is a detail view showing how a gear is mounted to control the speed of the stock feed. Fig. 6 is a view similar to Fig. 3, but showing a modification of the machine which adapts it to the purpose of cutting box blanks, and Fig. 7 is a detail of one of such blanks.

The machine is provided with a suitable frame 10 on the top of which is a table 11, over which the sheet stock 12 is fed as shown in Fig. 3. This stock may be veneer or other material. On the table are gages 13 which are adjustable, and which can be set to fit a sheet of stock of any desired width within the limits of the width of the machine. No novelty is claimed for any of the above arrangement.

The stock is fed forward into the machine by feed rollers 14 which have roughened surfaces, and which are arranged at the inner end of the table 11 so as to impinge on the stock and carry it into the machine. These rollers are mounted on shafts 15 and 16, and have vertically adjustable bearings as shown at 17 so that they can be raised or lowered to suit different thicknesses of stock. This arrangement is not novel, and is not referred to in detail.

The shafts 15 and 16 carry rotary scoring knives 18 and 19 which shear past one another, and are spaced the necessary distance apart so as to cut the stock 12 into parallel strips. The shafts 15 and 16 are connected by gears 20 and 21 so that they will turn in unison but oppositely, and the shaft 15 is moved by a gear wheel 22 which in turn

meshes with a gear wheel 22^a secured to a stud 23, the latter turning in a box 24 which is adjustable in a slot 24^a of the strap or bracket 25, this having one end extending over the shaft 15, and the other secured to the machine frame as shown in Fig. 2. The stud 23 also carries a gear wheel 26 meshing with and driven by a gear wheel 27 on the main shaft 28. It will be seen, therefore, that by changing the gear 22^a on the stud 23, and replacing it with a larger or smaller one as desired, and then adjusting the bearing of the stud so as to have the gear 22^a mesh with the gear 22, the speed of the stock feed can be regulated.

It will be noticed that the teeth of the gears 26 and 27 mesh loosely so as to permit a certain amount of lost motion, and this amounts in fact to an intermittent feed, the purpose of which will be hereinafter described. The shaft 28 carries a cutter head 29 which will be hereinafter referred to, and between the blades of which the stock enters. The shaft is provided with tight and loose pulleys as shown at 30, though it can be driven by any approved means.

As the stock 12 is fed into the machine by the feed rollers 14, it passes between spring feed plates 31 and 32 which are spaced apart and arranged one above the other as best shown in Fig. 3, the upper plates being secured to the cross-piece 33 on the machine frame (see Fig. 1) and the lower plates being secured in a recess 34 at the inner end of the table 11 as shown in Fig. 3. These spring feed plates have the necessary resiliency to permit the stock to move slightly up or down, and they carry the stock over the cut-off knife 35 which extends the entire width of the stock feed, and is secured to the sliding block 36. The knife can be attached and adjusted in any usual way, and as shown it has slots 37 which receive fastening bolts 38 extending into the block 36 while the knife can be set up vertically by means of bolts 39 extending through a part of the block and abutting with the lower edge of the knife. Nothing novel is claimed for this fastening arrangement, and any suitable fastening means for the knife can be employed.

The block 36 is recessed in its middle portion so that the ends overlap the ends of the cutter head 29 as shown in Figs. 1 and 3, thus leaving the edge of the knife 35 in close proximity to the cutter head, so that the blades of the latter can shear past it as the cutter head rotates. An important feature of the arrangement of the cut-off knife is that it is constantly sliding. This sliding can be effected in any convenient way, but as shown the knife block has a dovetailed tongue 40 sliding on a correspondingly shaped part of the frame, and 65 has at the end a bracket or arm 41 which is

grooved as shown at 42 to receive the cam collar 42^a on the shaft 28, so that as the shaft rotates, the knife block 36 and the knife 35 which it carries, will slide constantly backward and forward.

The cutter head 29 has radial blades 43 (see Figs. 1 and 4) which are spaced apart so that the stock 12 can readily enter between them, and the depth between the blades is sufficient to permit the stock to enter to any necessary extent. These blades are preferably, though not necessarily, detachable, and fit in corresponding grooves in the head 29, and they are also preferably hooked slightly as shown at 44 in Fig. 4, so that this hooked portion will form an edge which will readily enter the part of the stock which overlaps the cut-off knife 35 and shear past the cut-off knife so as to impart a clean cut to the severed portion of the stock. Obviously these blades can be integral with the head, and the shape of their cutting edge is not absolutely essential.

It will be seen that as the stock 12 is fed between the blades 43, the latter will carry the stock forcibly against the edge of the knife 35, and the stock will be cleanly cut between the blades and the knife, after which the severed portions will be carried down and delivered into the chute 46 which is prepared to receive them. The advantage of the arrangement described is that the cutting is much smoother than in ordinary machines of this nature, and the operation is wonderfully rapid. It will be noted that there can be any desired number of blades on the head 29, that numerous strips of stock can be fed over the knife edge 35, and that all the strips are simultaneously cut and the machine is capable of being highly speeded.

Another important feature of the arrangement of the blades of the cutter head and the sliding knife 35 is that the blades and knife do not dull readily, owing to the manner in which they move with relation to each other, and the stock is cut with comparatively little consumption of power.

In Fig. 6 I have shown how the machine can be very easily adapted to cutting box blanks such as are used for making wood boxes for matches, or for cutting sheet stock for other small box blanks. In adapting the machine for this purpose the cutter head is made with the blades 43 farther apart, and with deeper recesses between them, as the blanks are necessarily wider than match splints, toothpicks, or the like, and the feed is of course made to carry the stock 12 forward the right distance over the cut-off knife 35. I arrange an extra set of feed rollers 47 and 48 (see Fig. 6) behind the feed rollers 14, so that the stock will be held perfectly flat on the table 11 between the inner and outer set of feed rollers. Stationary scoring knives 49 are arranged in a crossbar

50 which is attached to the main frame so as to plow out V shaped scoring grooves 51 at parts corresponding to the corners of the blank 52, and the scoring knives 18 and 19 5 are placed the right distance apart to cut the stock 12^a into strips the width of the blank 52. The machine otherwise works precisely as already stated, that is to say the stock is fed forward by the feed rollers 14 and the rollers 47 and 48, is scored by the scoring knives 49, is slit into strips of the right width by the score knives 18 and 19, and is cut off by the knife 35 and blades 43, as already stated.

15 Attention is called to the fact, which will be readily seen by reference to Fig. 2, that when the stock is being cut off by reason of the blades 43 shearing across the edge of the knife 35, the feed will be stationary because 20 of the lost motion between the teeth of the gear wheels 26 and 27.

I claim:—

1. A machine of the kind described comprising a rotatable cutter head having radial 25 blades spaced apart from each other, a longitudinally sliding knife block moving parallel with the axis of the cutter head, a cam turning in unison with the cutter head and connected with the knife block to slide it, a 30 cut-off knife secured to the knife block with its edge shearing across the blades of the cutter head, and means for feeding stock across the edge of the cut-off knife and between the blades of the cutter head.

35 2. A machine of the kind described comprising a longitudinally sliding cut-off knife, a rotating head having blades spaced apart and moving near the edge of the cut-off knife, and means for feeding sheet stock 40 across the edge of the cut-off knife and into the recesses of the cutter head.

3. A machine of the kind described comprising a longitudinally reciprocating cut-off knife, a rotating cutter head having its 45 axis parallel with the cut-off knife, blades on the cutter head spaced apart and moving in close proximity to the cut-off knife, and means for feeding sheet stock across the edge of the cut-off knife and between the 50 blades of the cutter head.

4. A machine of the kind described comprising a rotating cutter head having radial blades spaced apart, a longitudinally reciprocating cut-off knife arranged opposite the 55 cutter head and at a tangent to the face of the cutter head, whereby the blades of the cutter head shear against the edge of the cut-off knife, and means for feeding sheet stock across the edge of the cut-off knife and between the blades of the cutter head.

5. A machine of the kind described comprising a rotatable cutter head having radial blades spaced apart from each other, a longitudinally sliding knife block recessed to receive the cutter head and with its end por-

tions overlapping the edges of the cutter head, and a cut-off knife secured to the knife block and with its edge arranged to shear across the outer portions of the cutter head blades.

70 6. A machine of the kind described comprising a rotating cutter head having radial blades spaced apart from each other, a longitudinally sliding cut-off knife arranged adjacent to the cutter head so as to shear 75 across the blades of the cutter head, and means for adjusting the knife with relation to the cutter head.

7. A machine of the kind described comprising a rotating cutter head having radial 80 blades spaced apart from each other, a longitudinally sliding cut-off knife arranged at a tangent to the cutter head and with its edge shearing across the outer portions of the cutter head blades, and a cam mechanism 85 for imparting motion to the cut-off knife.

8. A machine of the kind described comprising a rotating cutter head having radial blades hook shaped in cross section, and a longitudinally sliding knife parallel with 90 the axis of the cutter head and with its edge arranged to shear across the hooked edges of the cutter head blades.

9. A machine of the kind described comprising a rotating cutter head having radial 95 blades spaced apart from each other, a longitudinally sliding cut-off knife parallel with the axis of the cutter head and with its edge in close proximity and tangential to the outer portions of the cutter head blades, feed rollers to feed sheet stock to the cutter head and across the edge of the cut-off knife, and scoring knives arranged in sets to slit the stock into sheets.

10. A machine of the kind described comprising a rotating cutter head having parallel blades spaced apart from each other, a longitudinally sliding cut-off knife shearing across the face of the cutter head, feeding means to feed sheet stock across the cut-off knife and between the blades of the cutter head, and resilient guide plates extending from the feeding means to a point adjacent to the edge of the cut-off knife.

11. A machine of the kind described comprising a rotating cutter head having knives spaced apart on its face, a longitudinally sliding cut-off knife with its edge adjacent to the face of the cutter head, feeding means to feed sheet stock across the edge of the cut-off knife and between the blades of the cutter head, and means for changing the speed of said feeding means.

12. A machine of the kind described comprising a constantly rotating cutter head 125 having blades spaced apart on its face, a longitudinally sliding cut-off knife parallel with the cutter head and with its edge near the face of said cutter head, and an intermittent feed for feeding the stock across the 130

edge of the cut-off knife and between the blades of the cutter head.

13. A machine of the kind described comprising a rotating cutter head having blades spaced apart on its face, a cut-off knife sliding longitudinally parallel with the axis of the cutter head with its edge adjacent to the blades of the cutter head, means for feeding stock across the edge of the cut-off knife and between the blades of the cutter head, means for slitting the stock into parallel strips, and means for scoring said strips.

14. A machine of the kind described comprising means for feeding sheet stock, a cut-off knife movable longitudinally and transversely of said stock feed and with its edge arranged to come in contact with the stock, and means rotating opposite the knife for moving the stock against the edge of the cut-off knife to sever it. 15
